UNITED STATES PATENT OFFICE.

GUSTAV B. KEIL, OF CHICAGO, ILLINOIS, ASSIGNOR TO FEDERAL SIGN SYSTEM (ELECTRIC), OF CHICAGO, ILLINOIS, A CORPORATION OF NEW YORK.

GEARING.

1,245,109.

Specification of Letters Patent. Patented Oct. 30, 1917.

Application filed August 19, 1916. Serial No. 115,799.

To all whom it may concern:

Be it known that I, GUSTAV B. KEIL, a citizen of the United States, and a resident of Chicago, in the county of Cook and State 5 of Illinois, have invented certain new and useful Improvements in Gearing; and I do hereby declare that the following is a full, clear, and exact description thereof, reference being had to the accompanying drawings, and to the letters of reference marked thereon, which form a part of this specification. 10

This invention relates to improvements in gearing and consists of the matters herein- 15 after set forth and more particularly pointed out in the appended claims.

The improved gearing is of especial advantage for use with a washing machine of the cylinder or drum type and is shown here- 20 in as applied to such a machine. It is also adapted for driving a wringer mounted on said washing machine.

The many advantages of my invention will appear as I proceed with my specifica- 25 tion.

In the drawings:

Figure 1 is a view representing a front end elevation of a washing machine to which a gearing embodying my invention is ap- 30 plied.

Fig. 2 is a view representing a longitudinal vertical sectional view through the same, the plane of the section being indicated by the line 2—2 of Fig. 1.

Fig. 3 is a view representing a transverse vertical section through Fig. 2 in a plane indicated by the line 3—3 of Fig. 2.

Fig. 4 is a view representing a detail side elevation of a part of my gearing as viewed 40 in a plane indicated by the line 4—4 of Fig. 1.

Fig. 5 is a view representing a longitudinal detail section through a rack bar used in my gearing.

Fig. 6 is a view representing a detail vertical section, the plane of which is indicated by the line 6—6 of Fig. 1.

Fig. 7 is a view representing a transverse horizontal section through one end of the 50 washing machine the plane of the section being indicated by the line 7—7 of Fig. 1.

Fig. 8 is a view in perspective of a bracket member or plate which carries and forms

part of the gearing, as it appears when assembled and ready for attachment to a 55 washing machine.

Fig. 9 is a detail view in transverse section, the plane of the section being indicated by the line 9—9 of Fig. 1.

Referring now in detail to that embodiment of my invention as illustrated in the drawings, 10 indicates a main support for the gearing which, as illustrated in this particular instance, is the tub of a washing machine of the drum or cylinder type. The 60 tub is mounted at its corners upon upright front and rear pairs of legs 11, 11^a and 12, 12^a respectively. Said legs are preferably made of angle bars, placed so that the angles of the bars define the corners of the 65 support. The front pair of legs 11, 11^a are braced or connected at their top ends by a transversely extending angle iron 13 (see Fig. 2) the horizontal flange of which is spaced from the top ends of said legs, while 70 its vertical flange is arranged in the plane of the front faces of the said legs. The legs of each front and rear pair are connected together near their bottom ends by transversely 75 extending brace bars 14—14^a respectively and 80 each leg of the front pair of legs is connected to the like leg of the rear pair of legs by means of longitudinally extending bars 15, 15, all of which act to connect the legs 85 securely together. Casters are preferably attached to the legs so that the support may 90 be easily moved.

The tub 10 is made of sheet metal and comprises a transversely rounded bottom wall 10^a, which terminates in upright side 90 walls 10^b, 10^b, and upright front and rear end walls 10^c, 10^d respectively. A cover or lid 10^e is hinged to the top edge of the upright rear wall 10^d.

The front wall 10^c of the tub is spaced 95 back of the vertical plane of the front legs 11, 11^a. A horizontal plate 10^f forms a fixed top closure for the space between said tub wall 10^c and the angle bar 13 at the top of the legs 11, 11^a. Said plate 10^f is bent about 100 the upright flange of said angle bar and terminates in an upright transversely extending wall 10^g arranged in the plane of the front faces of said front legs 11, 11^a. To the bottom edge of said wall 10^g is hinged 105 an apron 17, which carries spring slips at

its bottom edge adapted for engagement with the channel bar 14 to lock said apron in closed position.

18, 18 indicate longitudinally extending shields or bracing walls arranged adjacent the upright side walls 10^c of the tub and fixed at their ends to the front and rear legs respectively. Said shields not only act to strengthen the part of the tub with which they engage but have other functions which will appear as I proceed with my specification.

Within the tub 10 is mounted a cylinder or drum 20 which is adapted for an oscillatory or rocking movement in the tub in a familiar manner. Said cylinder is of the usual structure for washing machines of this type and comprises upright front and rear end walls 21—22, perforated transversely rounded bottom and side walls 24 and a horizontal top wall 25. In said top wall is provided the usual opening through which the clothing is introduced or removed from the cylinder, said opening being normally closed by 25 a removably attached slatted door 26.

Fixed to the rear end wall 22 of the clothes cylinder, in a plane above its center of gravity, is a trunnion 27. This trunnion is normally journaled in a bearing yoke 28 fixed to the end wall 10^a of the tub. Said yoke has an upwardly opening bearing slot or groove through which the trunnion is introduced to its associated bearing surface therein.

35 The front end wall 21 of the cylinder 20 has fixed to it a bearing plate 30 which is capable of detachable operative engagement with a horizontal, power-driven, rotary oscillating stud or shaft 31, which projects 40 through the front wall 10^c of the tub 10 in axial alinement with the trunnion 27.

It is apparent from the foregoing description that when the shaft 31 is at rest, the cylinder 20 may be removed from the tub by simply lifting it from its bearing upon the shaft 31 and the bearing yoke 28, the cover 10^c of the receptacle 10, of course, being first opened to permit such removal.

The tub 10 is provided on its rounded 50 bottom wall 10^c adjacent the rear end wall 10^a with a drain cock 32 and a sight glass 33 through which the operator may see the level of the water in the tub. (See Figs. 2-3). The upright front wall 10^c and horizontal extension wall 10^e of the tub, together with the shield walls 18—18 and apron 17 constitute a gear casing or compartment 34 (see Fig. 2) within the plane of the front legs 11, 11^a. In said casing is located the power driven gearing which imparts the required oscillatory movement to the cylinder 20 and which also operates a second mechanism, in this case a wringer.

35 indicates a bracket plate (see Fig. 8) upon which is mounted and carried the said

gearing or power transmitting mechanism. Said plate is located within and toward the bottom of the compartment or gear casing 34 and is rigidly fixed to the front legs 11, 11^a. It comprises a body 36 which is placed adjacent to the upright front wall 10^c of the tub and a plurality of horizontal, vertically spaced arms 37, 38, and 39, 40. The arms 37, 38, at the right hand end of the body terminate in forwardly extending bars 37^a, 38^a, 75 which are attached to the upright front leg 11^a. The arms 39, 40, at the left hand end of the body project forwardly and are attached to the other front leg 11. Intermediate its ends, at its top, the said bracket plate has 80 an overhanging, forwardly extending arm 41, which terminates in a depending flange 42 so arranged as to provide bearing for the outer end of the driving stud or shaft 31 before mentioned. The inner end of said 85 shaft has bearing in an apertured boss formed on the body 36 of said bracket plate.

43 indicates a horizontally disposed shaft which is the power shaft of the operating gearing. Said shaft is adapted for continuous rotary motion in one direction and is journaled at its inner end in the body 36 of the bracket 35 and at its outer end in a suitable aperture formed in the bottom end of the depending flange 42 of the arm 41. A 95 driven pulley 44 of quite large diameter is fixed to that end of said shaft which projects beyond the front face of the flange 42.

Fixed to the inner end of the shaft 43 adjacent to the body 36 of said bracket 35 is a 100 spur pinion 45 which meshes with a spur gear 46 of larger diameter, rotatively mounted on a stub shaft 47 fixed in said bracket in a plane to one side of (to the left) and below the shaft 43. Made integral with 105 said gear 46 and projecting forwardly therefrom is a spur gear 48 of smaller diameter which meshes with a larger spur gear 49 loosely mounted on a stub shaft 50 fixed to the bracket 35 in a plane to one side of (the 110 left) and above the shaft 47. This large gear 49 has a crank pin 51 to which is operatively connected a rack bar indicated as a whole by the reference numeral 52.

The rack bar 52 is adapted to impart a rotary oscillating movement to a segmental gear 55 loosely mounted on the shaft 31 in a plane adjacent to the depending flange 42. A roller 53 loosely mounted on the shaft 43 supports the free end of said rack bar in 120 such position that it will always be in operative engagement with the segmental gear. The inner or rear face of the hub of said segmental gear has clutch teeth 55^a which are adapted to be engaged by like teeth formed 125 on a clutch collar 56 (see Fig. 2) feathered to the shaft 31, so as to be movable endwise thereon.

The clutch collar 56 may be shifted on the shaft 31, into and out of engagement with 130

the clutch teeth 55^a formed on the hub of the segmental gear 55, by means of an arm 60 fixed to the inner end of a transversely extending rock shaft 61; said shaft has bearing at one end in a lug 61^a on the bracket body 36 and at its other end in the arm 39 of said bracket. The arm 60 has a lug at its bottom end which engages within the groove of said clutch collar and at its top, said arm 10 is connected to a spring 62 which is fixed to a horizontal rib at the top edge of said bracket 35. The spring 62 holds the arm 60 at either limits of its movement, that is to say, when the clutch collar is either operatively engaged with or disengaged from the associated clutch teeth on the hub of the segmental gear 55. The outer end of said rock shaft 61 projects through a suitable aperture in the shield wall 18 adjacent the 15 upright leg 11 and is provided without said wall with an operating lever 63.

It is apparent from the foregoing description that the continuous rotary movement of the shaft 43 is imparted to the gear 25 49 at a slower speed by means of the intermediate speed reducing gears 45—46—48 before mentioned, and that the rotary motion of said gear 49 is transposed into a rotary, oscillatory movement of the segmental gear 55, which movement is transmitted to the cylinder 20 when the controlling lever 63 is in the required position.

To reduce the shock and wear between the segmental gear 55 and the rack bar 52 at the 35 ends of the stroke, the rack bar is (see Fig. 5) provided with a longitudinal upwardly opening groove 52^a in which is located a second bar 52^b provided with the rack teeth. The second bar is somewhat shorter than 40 the groove 52^a and springs 52^c are placed at its ends to absorb and reduce the shock or jar when the movement of the rack bar as a whole is reversed.

The pulley 44 on the shaft 43 is connected 45 by a belt 57 to a smaller pulley 58 on the shaft of a motor 59, which is carried by the bracket 35 as follows:—64, 65, indicate arms fixed to the bracket 35 and depending below the rounded bottom wall 10^a of the tub 50 10, where they are provided with horizontal extensions 64^a, 65^a. The extension 65^a is attached to the front leg 11^a. Parallel, horizontal rods 66, 66 connect the arms 64^a, 65^a (see Fig. 9) and angle bars 67, 67, 55 slidably mounted upon said rods provide a carriage from which depends the motor 59. A thumb screw 68 carried by the arm 65^a and threaded through the adjacent angle bar 67 provides means for adjusting the position of the motor carriage in either direction to secure the proper tension of the driving belt 57.

The motor is thus located in a plane below the tub and within the tub legs, where it is 60 65 out of the way and protected from the

water that may be splashed from the tub. In addition the motor is insulated from the support and so placed, it balances the weight of the driving gearing on the bracket 35.

To further protect the motor, I provide a plate 69, which has an upright, rear flange 69^a fixed to the hanger arm 64 of the bracket plate 35 and a depending front flange 69^b attached at its bottom to the transverse 75 brace 14 that connects the front tub legs 11—11^a. Said front flange is spaced back of the front plane of the legs 11, 11^a to leave space for the belt and pulleys 57, 58, and 44.

The connection between the gearing and 80 the wringer is as follows:—70 indicates the wringer which is placed at the front of the tub with its upright frame members 71—71 attached to the angle iron 13, that connects the top ends of the front legs 11, 11^a. 72, 85 73 indicate the upper and lower rolls of the wringer. The lower wringer roll 73 has its shaft 74 extended beyond the wringer frame (to the left as viewed in Fig. 1) where it has bearing in an upright standard 75 fixed 90 to the top end of the front leg 11. Secured to the end of said shaft is a sprocket wheel 76 (see Fig. 4) which is operatively driven by means of a sprocket chain 77 from a smaller sprocket wheel 78 fixed to the end 95 of a shaft 79, which has bearing in the arms 39—41 of the bracket 35.

Loosely mounted on the shaft 79 are oppositely facing bevel gears 80, 81, which are provided on their opposed faces with 100 clutches 80^a, 81^a. Said gears mesh with a larger bevel gear 82 fixed to and co-axial with a spur gear 83 mounted upon a stud 84 (see Fig. 6) which projects forwardly from the bracket 35. The spur gear 83 is 105 driven by the gear 49. A clutch collar 86 is keyed to the shaft 79 intermediate the gears 80—81 and is adapted to engage either of the clutches 80^a, 81^a of the gears 80, 81, so that the shaft 79 may be driven in either direction or the said clutch collar may be held in an intermediate or neutral position so that, even though the bevel gear 82 be rotating, the shaft 79 will remain inoperative. A bell crank lever 87 mounted on a stud 88 110 on the bracket 35 vertically above the stud 84 has its depending arm 89 operatively engaging the clutch 86. A laterally extending arm 90 of said bell crank lever projects through an aperture 91 in the shield wall 18 115 120 in a position above the sprocket 78. A link 92 connects the arm 90 with an arm 93 of a lever 94 mounted on a lug 95 made integral with the standard 75. The top end of said lever 94 is provided with a handle 96 having 125 a detent which coacts in a familiar way with notches 97, 98, 99 (see Fig. 4) formed in a flange at the top of the standard 75. The said notches correspond with the two-engaging and the neutral positions of the clutch 130

21
 collar 82 relative to the gears 80—81. A cover plate 100 fixed to the standard 75 and adjacent front leg 11, incloses the sprocket wheels 76, 78, the associated chain 77, the major portion of the lever 94 and the link 92. It is apparent from the foregoing description that the lever 94 may be shifted into and locked in position so that the shaft 74 of the wringer may be driven in either 10 direction from the gear 82, or said lever may be locked in the intermediate position when the shaft 74 will remain idle though the gear 82 be rotating.

15 The operation of a washing machine embodying my invention is as follows:

The clutch 56 controlling the operation of the cylinder 20 is normally disengaged from the segmental gear 55 and the said cylinder is at rest. Likewise the clutch 86 is in a neutral or intermediate position, so that the wringer rolls are idle. The shaft 43, however, after the motor 59 is started, is driven continuously in one direction by said motor, as before described. To start the washing machine, the operator grasps the lever 63 and moves the same to bring the clutch 56 into engagement with the segmental gear 55, whereupon an oscillating movement is imparted to the cylinder 20. When the washing operation has been continued as long as desired, the lever 63 is again operated to remove the clutch 56 from its engagement with the segmental gear 55. Upon such disengagement the opposite face of the 30 clutch 56 thereof will engage against the adjacent face of the boss providing bearing for the inner end of the shaft 31, and act as a brake to slow down and finally stop the oscillation of the cylinder 20. On account 35 of the relative axial location of the shaft 31 and of the trunnion 27, which as before described are located above the center of the gravity of said cylinder, said cylinder will come to a position of rest with its top wall 40 25 in a horizontal position.

45 The controlling lever 94 may now be disengaged from its neutral locked position and be moved forwardly until the detent handle 96 engages within the notch 98 and a continuous rotary movement will then be imparted to the wringer rolls in a forward direction.

50 The clothing is now removed from the cylinder 20 and fed through the wringer in the ordinary fashion. In case one of the articles of clothing being passed through the wringer should wrap around the wringer rolls, as sometimes happens, the operator grasps the lever 94 and moves the same to engagement 55 with the notch 97 where the wringer rolls 72, 73 will rotate in a reverse direction, so that the entangling clothing may be disengaged.

55 The wringing operation may be continued 60 until all of the clothing in the cylinder 20

has been operated upon by said wringer, when its controlling lever is again moved to neutral position. Other clothing may now be introduced into the cylinder 20, its door 26 again replaced, the lid 10° closed, 70 when the operator may again move the lever 63 to positively engage the clutch 56 with the associated clutch teeth 55^a of the segmental gear 55.

75 It is apparent that a washing machine 75 provided with my improved gearing, possesses many advantages and one of them is, that the clothes receiving cylinder 20 is always brought to a position of rest with its top horizontal wall 25 in an uppermost position, 80 owing to the location of its supporting and driving connections with reference to its center of gravity. Another advantage is that with the structure shown, the bracket castings 35 and all of the driving gearing carried thereby together with the motor may be assembled before it is introduced and attached in place within the gear case or compartment provided therefor. A further advantage exists in the fact 90 that the entire assembled gearing is located in a plane within the upright vertical plane of the front legs 11, 11^a, thereby inclosing all parts so that less damage is liable to occur when in shipment. Another advantage is apparent from this construction. The most usual way to shift the support as a whole about, when through with the same, or when starting in with a washing, is to push it forwardly, with the hands 100 of the operator grasping the rear top edge of the support. Heretofore, gearing for similar purposes have generally been located outside of and horizontally beyond the base provided by the legs of the support or tub, 105 and in so moving the support from place to place, upon engagement of the casters on the front legs, with some obstruction, a short push at the rear of the machine always has caused tipping over. With the construction 110 110 as shown and described in the present invention, the entire weight of the gearing is within the base of the support, therefore this danger of tipping over is obviated.

115 While in describing my invention I have referred to certain details of mechanical construction and arrangement of parts, I do not wish to limit myself thereto, except as may be pointed out in the appended claims.

120 I claim as my invention:

1. In combination, a support having upright end walls, legs for said support, one of said end walls being spaced inwardly from the legs of that end of the support, a bracket plate mounted within the space between the said last named legs and the associated end wall of said support, an operating device within said support, an operating shaft and gearing carried by said bracket plate, said operating device being 125 130

capable of detachable connection with said operating shaft, and a motor carried by said bracket plate for driving said gearing.

2. In combination, a support having upper 5 right end walls, legs for said support, one of said end walls being spaced inwardly from the legs of that end of the support, a bracket plate mounted within the space between the said last named legs and the associated 10 end wall of said support, an operating device within said support, an operating shaft and gearing carried by said bracket plate adapted for operative connection with said operating device, arms depending from 15 said bracket plate into a plane below said gearing, a motor carried by said arms, and means connecting said motor and said gearing.

3. In combination, a support having upper 20 right end walls, legs for said support, one of said end walls being spaced inwardly from the legs of that end of the support, a bracket plate mounted within the space between the said last named legs and the associated end 25 wall of said support, an operating device within said support, an operating shaft and gearing carried by said bracket plate adapted for operative connection with said operating device, arms depending from said 30 bracket plate into a plane below said support, a carriage movably supported by said arms, and a motor for driving said gearing mounted on said carriage.

4. In combination, a support having upper 35 right end walls, legs for said support, one of said end walls being spaced inwardly from the legs of that end of the support, a bracket plate mounted within the space between the said last named legs and the associated 40 end wall of said support, an operating device within said support, an operating shaft and gearing carried by said bracket plate capable of detachable operative connection to 45 said operating device, arms depending from said bracket plate and a motor for driving said gearing carried by said arms, said gearing and motor being located in planes on opposite sides of said operating shaft.

5. In combination, a support having upper 50 right end walls, legs for said support, one of said end walls being spaced inwardly from the legs of that end of the support, a bracket plate within the space between the said last named legs and the proximate end 55 wall of said support, said bracket plate being fixed to said legs, an operating device within said support, an operating shaft and gearing carried by said bracket plate, said operating device being adapted for operative engagement with said operating shaft, a motor carried by said bracket plate for driving said gearing, and shields or plates carried by said support forming with the said proximate end wall a casing for said gearing, one 60 of said shields being a door adapted to

completely inclose said gearing, and being hinged at its top end.

6. In combination, a support having upright end walls, legs for said support, one of said end walls being spaced inwardly 70 from the legs of that end of the support, a bracket plate having a plurality of arms located within the space between the said last named legs and the associated end wall of said support, an operating device within 75 said support, an operating shaft and gearing carried by said bracket plate, said operating device being adapted for operative engagement with said operating shaft, and a motor for driving said gearing, several of 80 said bracket arms being rigidly fixed to said last named legs, the rest of said arms carrying said motor.

7. In combination, a support having upright end walls, legs for said support, one 85 of said end walls being spaced inwardly from the legs of that end of the support, a bracket plate having a plurality of arms located within the space between the said last named legs and the associated end 90 wall of said support, an operating device within the said support, an operating shaft and gearing including a driven pulley carried by said bracket plate, said operating device being adapted for operative engagement with said operating shaft, a motor having a driving pulley, a belt operatively connecting said motor and gearing pulleys, several of said bracket arms being adapted 95 for attachment to said last mentioned legs, the rest of said arms depending below the plane of said gearing and supporting said motor, and means on said last mentioned arms for adjusting the position of the motor to provide the proper tension in said 100 driving belt.

8. In combination, a main support having upright end walls, legs for said support, one of said end walls being spaced inwardly from the legs at that end of the support to 110 provide a gear casing, a gearing and supplemental support adapted for attachment to the said main support within said gear casing, said gearing including an oscillating shaft, an operating device within said support adapted for removable attachment to said oscillating shaft, a motor carried by said supplemental support and driving said gearing, a second operating device carried by said support and driven from said gearing carried by said supplemental support and means without said main support for controlling the operative movement of said gearing relative to said operating devices.

9. In combination with a main support 125 containing an operating device, coacting means on said support and on said operating device providing a bearing support for one end of said operating device, a gearing and a supplemental support therefor, adapt- 130

ed to be attached to said main support, said gearing including a shaft which is coaxial with said bearing support and which is capable of oscillating, rotary movement, 5 means carried by the other end of said operating device adapted for removable supporting engagement upon said gearing shaft, said means operatively connecting said operating device with said shaft, and a motor 10 carried by said supplemental support for driving said gearing.

10. In a mechanism of the kind described, in combination, a main support having upright walls, an operating device within said support adapted for an oscillatory movement, a supplemental support adapted for attachment to said main support, an oscillatory shaft and gearing for imparting movement to said shaft carried by said supplemental support, said oscillatory shaft projecting through one of the upright walls of said main support, means for operatively connecting and disconnecting said oscillatory shaft from said gearing, and means on 25 said operating device above the center of gravity thereof for removable attachment to said oscillatory shaft, said parts being so constructed that the operating device within the main support will stop in a predetermined position when said oscillating shaft 30 is disconnected from the driving influence of said gearing.

11. A gearing device of the kind described, comprising a support, an oscillatory operating device in said support, an operating shaft adapted to be operatively engaged by said operating device, a segmental gear having a clutch face loosely mounted on said operating shaft, a clutch collar feathered 40 on said operating shaft and adapted to engage the clutch face of said segmental gear, a reciprocating rack bar engaged with said segmental gear, a driven shaft parallel to said operating shaft, a roller loosely mounted 45 on said driven shaft and supporting said rack bar, and a large gear spaced laterally from said driven shaft and operatively connected thereto, said large gear having a crank pin operatively connected to said rack bar.

12. A gearing device of the kind described, comprising a support, an oscillatory operating device in said support, an operating shaft adapted to be operatively engaged by said operating device, a segmental gear having a clutch face loosely mounted 55 on said operating shaft, a clutch collar feathered on said operating shaft and adapted to engage said segmental gear, a reciprocating rack bar engaged with said segmental gear, a driven shaft parallel to 60 said operating shaft, a roller loosely mounted on said driven shaft and supporting said rack bar, said rack bar comprising a chan-

nel member closed at its ends, a tooth bar longitudinally movable in said channel 65 member and shock absorbing devices interposed between the ends of said tooth bar and the closed ends of said channel member, a large gear spaced laterally from said driven shaft and operatively connected 70 thereto, said large gear having means connecting said rack bar to said large gear.

13. A gearing device of the kind described, comprising a support, an oscillatory operating device in said support, an operating shaft adapted to be operatively engaged by said operating device, a segmental gear having a clutch face loosely mounted on said operating shaft, a clutch collar feathered 80 on said operating shaft, said clutch collar having on one end clutch teeth adapted for operative engagement with said segmental gear and on its other end a friction face adapted for operative engagement with a fixed part of said support, a reciprocating 85 rack bar engaged with said segmental gear, a driven shaft parallel to said operating shaft, a large gear spaced laterally from said driven shaft and operatively connected thereto, a crank pin on said large gear operatively connected to said rack bar and anti-friction means for supporting the free end 90 of said rack bar to hold it in operative engagement with said segmental gear.

14. A gearing device of the kind described, comprising a support, an oscillatory operating device in said support, an operating shaft adapted to be operatively engaged by said operating device, a segmental gear having a clutch face loosely mounted on 100 said operating shaft, a clutch collar feathered on said operating shaft, said clutch collar having on one end clutch teeth adapted for operative engagement with said segmental gear and on its other end a friction face 105 adapted for operative engagement with a fixed part of said support, means for normally holding said clutch collar in either of its operative positions, a reciprocating rack bar engaged with said segmental gear, a 110 driven shaft parallel to said operating shaft, a large gear spaced laterally from said driven shaft and operatively connected thereto, a crank pin on said large gear operatively connected to said rack bar and 115 an antifriction means for supporting the free end of said rack bar to hold it in operative engagement with said segmental gear.

In testimony that I claim the foregoing as my invention I affix my signature in the 120 presence of two witnesses this 21st day of March, A. D. 1916.

GUSTAV B. KEIL.
